UNITED STATES PATENT OFFICE.

BENJAMIN J. HARRISON, OF NEW YORK, N. Y.

DESIGN FOR CHAIR-FRAMES.

Specification forming part of Design No. 6,658, dated May 20, 1873; application filed April 1, 1873.

To all whom it may concern:

Be it known that I, BENJAMIN J. HARRISON, of the city and State of New York, have invented a Design for Chair-Frames, of which the following is a specification:

In the accompanying drawing the design of the shape and configuration of such chair-frame is represented by a side view, Figure 1, of the chair complete, and by an edge view, Fig. 2, of one side frame.

The said frame is made of two cross-legs, *a* and *b*. The general conformation is slightly tapering from the intersection at *c* to the respective ends; but the design relates to imitation rustic-work, carved with projections *i* *i*

at alternate opposite sides of the respective legs, the same forming imitation knots that ornament the edges of the frame or legs at each side, and the parts are rounded, as represented.

I claim as my invention—

The design of the shape and configuration of the chair-frame, as described and represented.

Signed by me this 25th day of March, A. D. 1873.

B. J. HARRISON.
